CLAIM

The ornamental design for a syringe pump, as shown and described.

DESCRIPTION

FIG. 1 is a front, top, and right-side perspective view of the syringe pump, showing our new design;
 FIG. 2 is an upwards sectional view thereof taken from the indicated cut plane in FIG. 1;
 FIG. 3 is a downwards sectional view thereof taken from the indicated cut plane in FIG. 1;
 FIG. 4 is a front elevational view thereof;
 FIG. 5 is a back elevational view thereof;
 FIG. 6 is a right-side elevational view thereof;
 FIG. 7 is a left-side elevational view thereof;
 FIG. 8 is a top plan view thereof; and,
 FIG. 9 is a bottom plan thereof.

The ornamental design which is claimed is shown in solid lines in the drawings. The broken lines depict portions of the syringe pump that form no part of the claimed design.
